UNITED STATES PATENT OFFICE.

PAUL W. JANNOCH, OF PASADENA, CALIFORNIA.

GLASS-HOUSE ROOFING.

1,397,762.

Specification of Letters Patent. Patented Nov. 22, 1921.

Application filed January 2, 1920. Serial No. 348,998.

To all whom it may concern:

Be it known that I, PAUL W. JANNOCH, a citizen of the United States, residing at Pasadena, in the county of Los Angeles and 5 State of California, have invented new and useful Improvements in Glass-House Roofing, of which the following is a specification.

This invention relates to building construction and more particularly to roofing, and has for its object to provide an improved roofing member in the nature of a transparent or semi-transparent tile, and which can be advantageously used in houses 15 or buildings wherein transparent or semi-transparent roofs are desired, and the invention consists of the construction and details embodiments of which are illustrated in the accompanying drawings and described 20 and claimed herein.

Figure 1 is a perspective of a portion of a glass-house roof.

Fig. 2 is a perspective of one of the improved cover plates.

Fig. 3 is a perspective of one of the plates showing its upper edge as modified for arrangement at a hip line of a roof structure.

Fig. 4 is a perspective of a ridge plate.

Fig. 5 is a perspective of a portion of the 30 roof as constructed with the improved roof and ridge plates.

Fig. 6 is a sectional view showing the arrangement of the ridge or hip plates and the subjacent plates.

It is understood that the improved roof construction may utilize plates, of the type hereinafter described, that may be made of different material according to the purpose in addition to the usual covering property of 35 the roof, and in the present case the improved roof structure is illustrative of the application of the invention to the construction of glass-houses in which case the roof forming plates or members are of translucent or transparent material, but as above indicated the roof forming plates may be of 45 any suitable material and therefore may be opaque.

In the construction of the improved roof 50 a suitable framework is erected comprising transverse stringers 2 spaced in parallelism a suitable distance apart along rafters 3 that may be suitably supported by an underpinning or studding 4, the stringers 2—2 being preferably of small transverse dimen-

sions but of such size as to be of sufficient strength to serve their purpose which is to serve as a hanger for the roofing plates or tile, one of which is shown in perspective in Fig. 2 as comprising a generally plane body part or panel 5 of suitable length and width and having along its longitudinal edges flanges one of which is shown at 6 as deflecting slightly outwardly from the plane of the panel 5 while the other flange 7 is deflected in an opposite direction or inwardly with respect to the plane occupied by the body or panel 5.

The flanges 6 and 7 are equal in width and they occupy the same relative angular planes 70 with respect to the plane occupied by the body 5 of the panel, and as a result of such construction, the entire under face of flange 7 makes direct contact with the entire upper face of flange 6 of the next adjacent member 75 when the plates or tiles are assembled to form a roof.

At one end of the panel 5 and on the under face thereof there is provided a hook 8 having an inner recess 9 of such area as to readily receive the body of the stringer 2 over which the plate or tile is laid and on which it is hooked, as clearly shown in Fig. 1. In such arrangement of the plates the outwardly deflected flange 6 of one tile or plate 85 forms substantially a channel that is overhung by the superposed marginal flange 7 of the next adjacent plate 5; each of these plates as hung from one stringer 2 being arranged in suitable spaced relation and 90 having their contiguous edges overlapped throughout the course or stringer, and the plates of the next higher stringer or course having their lower ends overlapping the upper ends of the next lower course or belt so 95 as to efficiently shed water draining down the superposed plates or tiles.

To facilitate the construction of a hip or ridge as shown in Fig. 5, a set of plates 5 is provided, the upper transverse ends or 100 edges of the plates being flattened as at 10 into the plane of the body or panel 5 of the plate, the flattening of the upper ends of the plates being to such a depth along the upper ends of the plate as to provide for 105 the application thereto of ridge or hip forming plates or tiles one of which is clearly illustrated in Fig. 4.

The longitudinal ridge or hip plate designated 12 comprises an elongated body por-

tion of V-shape in cross section, the divergent lateral parts of the plate having an angle complementary to the angle of the opposite roof panels of the roof being constructed, and one end of each of the hip plates 12 is shown as deflected upwardly as at 13 while the opposite end is deflected downwardly as at 14, and these ends are matched with contiguous and complementary ends of other plates arranged in alinement along the ridge or hip of the roof as shown in Figs. 5 and 6.

From the above it will be seen that I have provided a roof tile or plate of simple and practical form that can be readily erected in place in the construction of a roof and which will be effective in the shedding of water and practically leak proof when in its properly laid position.

20 Various changes may be made without departing from the spirit of my invention as claimed.

I claim:

The herein described roof, composed of a plurality of assembled plates, each of which 25 comprises a substantially rectangular flat body portion, flanges projecting from the sides of said body portion, which flanges are equal in width and arranged in parallel planes that are inclined with respect to the 30 plane occupied by the body of the plate, said flanges overlapping throughout their entire widths, the corresponding flanges of the adjacent roof members when the latter are properly assembled, and which overlapping 35 flange arrangement causes the body portions of the members to occupy inclined planes when properly assembled, and thereby providing a roof structure having a plurality of parallel shallow channels.

In testimony whereof I have signed my name to this specification.

PAUL W. JANNOCH.
